UNITED STATES PATENT OFFICE.

THEODORE VON DER LÜHE AND WILLIAM H. BARTHOLOMEW, OF
NEW YORK, N. Y.

COMBINED CALENDAR AND PEN-RACK.

SPECIFICATION forming part of Letters Patent No. 746,540, dated December 8, 1903.

Application filed August 18, 1903. Serial No. 169,921. (No model.)

To all whom it may concern:

Be it known that we, THEODORE VON DER LÜHE and WILLIAM H. BARTHOLOMEW, both citizens of the United States, and residents 5 of the city of New York, borough of Manhattan, in the county and State of New York, have invented new and useful Improvements in a Combined Calendar and Pen-Rack, of which the following is a full, clear, and exact 10 description.

The present invention relates to certain novel and useful improvements in a combined calendar and pen-rack.

One of the principal objects of the invention 15 is to provide an improved calendar-stand which may be easily and readily folded or collapsed for the purpose of distributing or mailing the same; but when in its operative position the parts will be so correlated and 20 combined that the calendar-stand will be provided with a relatively wide base portion, so that the possibility of the stand containing the pen-rack being upset will be reduced to a minimum.

25 A further object of our invention is to form the calendar-stand of a single piece of material bent or scored to form hinges for assembling the blank in the form of a stand, said blank also having a tongue portion designed 30 to interlock with the portion of the blank forming the back of the stand.

As a further object we have also in view 35 providing the calendar-stand with a novel pen-holding rack especially designed and adapted for supporting fountain-pens in an approximately upright position, so that the ink will not drip from the pen-reservoir, and such pen-rack is also formed in such manner that dust, dirt, and similar material will not 40 accumulate therein.

To the accomplishment of the above-recited 45 objects and others of a similar nature the invention consists in the construction, combination, and arrangement of parts, as is described in this specification, delineated in the accompanying drawings, and set forth in the appended claims.

Reference is to be had to the accompanying 50 drawings, forming a part of this specification, in which similar characters of reference indicate corresponding parts in all the figures.

Figure 1 is a perspective view of a calendar-stand in its assembled position, such view also illustrating the manner of mounting the pen-rack thereon. Fig. 2 is a sectional view taken 55 through the pen-rack and the portion of the calendar-stand to which it is secured. Fig. 3 is a detail perspective view of the pen-rack; and Fig. 4 is a plan view of the blank from which the calendar-stand is formed, such view 60 showing the manner of cutting and scoring the blank.

Referring now to the accompanying drawings in detail, A designates our improved calendar-stand as a whole, such stand being 65 formed of a blank such as is shown in Fig. 4. By reference to said figure it will be seen that the blank is approximately rectangular in shape, with the exception of one end portion 5, which is cut in the shape of a tongue, and 70 the blank is preferably scored transversely, as shown by the dotted lines in said figure, to form the base member 6, the front or face member 7, and back member 8, the latter being provided with a plurality of transversely- 75 arranged slots 9 and 10, the slot 10 being preferably of greater length than the slot 9, the intention being that when the blank is bent upon the scored lines it will form a stand of the character shown in Fig. 1. The 80 tongue portion 5 may be passed through the slots and be interlocked by the strip 11, formed by said slots. Instead of merely scoring the blank, if desired, transverse hinges of fabric or similar material may be employed 85 to connect the front, back, and base portions. The front or face of the stand is preferably provided with a calendar, such as shown at 12 in Fig. 1, and is designed to have secured thereto our improved pen-rack, which is 90 clearly shown in Figs 1, 2, and 3 and which we will now describe in detail. This rack is formed of tin, aluminium, or similar metal and comprises, essentially, a relatively long body portion 13, provided at one of its longitudinal edges with upwardly-curved lip portions 14 and 15, a space being formed between 95 said lips to enable the pen to be readily grasped. We have also arranged at various points along the longitudinal edges of the 100 body portion a number of projections or teeth, such as shown at 16, said teeth being

designed to penetrate the cardboard or material forming the front of the calendar-stand and then to be bent over and clenched upon the back thereof, as shown at 17 in Fig. 2, 5 whereby the rack will be securely attached to said stand. The body portion of the rack is relatively wider at one end than at the other, and said wider end is designed to form the lower portion of the rack when mounted in 10 the manner shown in Fig. 1. This lower widened end portion is formed with an end plate 18, which is intended to be bent upward until it comes into contact with the curved lip 15, such plate 18 having a straight side 15 edge portion 19, so that a space or opening 20 is left between the plate and the adjoining lip for the purpose of permitting dirt, dust, or the like to pass from the rack instead of remaining in the corners thereof. The remainder 20 of the face of the stand—that is to say, the portions other than occupied by the pen-rack and the calendar—may be employed for any suitable advertising matter, inscriptions, or the like. It will be also observed that we 25 have provided an exceedingly economical and convenient form of calendar and pen-rack, and, if desired, the rack portion may be placed transversely of the face instead of inclined, as shown in the drawings, and the end plate 30 18 omitted, so that pencils, penholders, and the like may be placed thereon; but when the rack is to be used for fountain-pens it is preferably secured in the manner illustrated.

Having thus described our invention, we 35 claim as new and desire to secure by Letters Patent—

1. The combination of a stand formed of a single blank of material by bending or scoring the same transversely, one end of the 40 blank having slots formed therein to receive and lock the opposite end of the blank and a pen-rack secured to said blank, substantially as set forth.

2. A combined calendar-stand and pen- 45 rack, comprising a blank designed to be folded

or bent to form a base portion, a face portion and a back portion, said back portion having a plurality of transverse slots therein, forming a locking-strip, a tongue portion formed on the base and designed to interlock with the 50 locking-strip of the back, and a pen-rack secured to the face portion of the stand, substantially as set forth.

3. The combination of a calendar-stand formed of a single piece of material bent into 55 an approximately triangular form to constitute a base portion, a face portion and a back portion, a pen-rack secured to said face portion, said rack comprising a relatively long body portion, a plurality of teeth formed longitudinally of the body portion and designed to engage with the face of the calendar, and upwardly-turned curved lip members formed integral with said body portion, substantially 60 as set forth.

4. The combination of a calendar-stand formed of a single piece of material bent into an approximately triangular form to constitute a base portion, a face portion and a back portion, a pen-rack secured to said face portion, said rack comprising a relatively long body portion, a plurality of teeth formed longitudinally of the body portion and designed to engage with the face of the calendar, curved 70 lip members formed integral with the body 75 portion at one of the longitudinal edges thereof, and an end plate bent at an angle to the body portion, adjacent to one of the lip members, an opening being formed between the end plate and the lip member for permitting 80 the passage therethrough of dirt, dust or the like, substantially as set forth.

In testimony whereof we have signed our names to this specification in the presence of two subscribing witnesses.

THEODORE VON DER LÜHE.
WILLIAM H. BARTHOLOMEW.
